REED FOR A REED SWITCH

Bernard Edward Shlesinger, Jr., 9411 Macklin Court,
Alexandria, Va. 22309

Filed July 9, 1974, Ser. No. 486,889

Term of patent 14 years

Int. Cl. D13—03

U.S. Cl. D26—13 R

FIG. 1 is a top plan view of a reed for a reed switch showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view of a modified form of the reed described in FIG. 1 showing my new design;

FIG. 7 is a front side elevational view thereof;

FIG. 8 is a rear side elevational view thereof;

FIG. 9 is a left side elevational view thereof;

FIG. 10 is a right side elevational view thereof;

FIG. 11 is a top plan view of a modified form of the reed described in FIG. 1 showing my new design;

FIG. 12 is a front side elevational view thereof;

FIG. 13 is a top plan view of a modified form of the reed described in FIG. 1 showing my new design;

FIG. 14 is a front side elevational view thereof;

FIG. 15 is a top plan view of a modified form of the reed described in FIG. 1 showing my new design;

FIG. 16 is a left side elevational view thereof;

FIG. 17 is a top plan view of a modified form of the reed described in FIG. 1 showing my new design;

FIG. 18 is a left side elevational view thereof.

The bottom plan views opposite to the top plan views of FIGS. 1, 6, 11, 13, 15 and 17 are identical to these respective figures.

The rear, left and right side elevational views of the reeds shown in FIGS. 11 and 13 are identical to FIGS. 3, 4 and 5 and FIGS. 8, 9 and 10 respectively. The front, rear and right side elevational views of the reeds shown in FIGS. 15 and 17 are identical to FIGS. 12, 3 and 5 and FIGS. 14, 8, and 5, respectively.

I claim:

The ornamental design for a reed for a reed switch, as shown and described.
